UNITED STATES PATENT OFFICE

99,891

DESIGN FOR A COMBINED PACKAGING, CUTTING AND SERVING TRAY

Thomas J. Pilliod, Swanton, Ohio, assignor to
The Pilliod Cabinet Company, Swanton, Ohio,
a corporation of Ohio

Application March 30, 1936, Serial No. 61,856

Term of patent 3½ years

To all whom it may concern:

Be it known that I, Thomas J. Pilliod, a citizen of the United States and resident of Swanton, county of Fulton, State of Ohio, have invented a new, original, and ornamental Design for a Combined Packaging, Cutting and Serving Tray, of which the following is a specification, reference being had to the accompanying drawing, forming a part thereof.

packaging, cutting and serving tray embodying the invention, and Fig. 2 is an edge view thereof.

I claim:

The ornamental design for a combined packaging, cutting and serving tray, substantially as shown.

In testimony whereof I have hereunto signed my name to this specification.

THOMAS J. PILLIOD.
